INTERNAL-COMBUSTION ENGINE

Arne Feroy, New York, N. Y.

Application March 18, 1944, Serial No. 527,063

7 Claims. (Cl. 123—73)

This invention relates to internal combustion engines and its object is to provide a simple engine of low cost, capable of high specific performance.

The simplest engine is the two-stroke cycle with crankcase scavenging. It has no valves and no separate blower—no moving parts for pumping air into the cylinder, the job being done by the lower side of the piston. The use of the piston for blower purposes is incidental and does not involve any additional mechanical losses or any additional parts or manufacturing cost. The work needed for scavenging is less than with any engine having a separate blower or scavenging pump. For example, to drive a rotary blower may require about 17% of the engine power, which amount would therefore not be available at the engine shaft. And of this power required to drive the blower, only about half would actually move air, the other half being dissipated in mechanical and other losses of the blower and its drive. Most rotary blowers have the "square" indicator card, showing about twice the work needed to move the same air by a piston compressor. All things considered, the work done in scavenging an engine by a separate blower is about twice that done by crankcase scavenging. The saving is available at the shaft of the crankcase scavenged engine to increase its net output, and in manufacture, the cost of the separate blower is also saved.

One disadvantage of the crankcase scavenged engine has been its inability to develop more than about 45 lbs./sq. in. BMEP. To get high specific performance, it is necessary to have complete scavenging, requiring a volume of air about 140% of the piston displacement, but the crankcase scavenged engine has only 100% of its piston displacement for pumping purposes, and with the losses usually present, it realizes only about 70% of that. Consequently it gets about half the air it ought to have for high performance. An object of this invention is to provide means for increasing the air flow thru the engine to what it should be for high performance, without adding complication to the engine. In other words, an object is to make a simple crankcase scavenged engine supercharge itself—to make the pumping action of the under side of the piston put more air into the engine than the piston displacement.

In the drawing, Fig. 1 is a transverse sectional view of an engine constructed in accordance with the invention; Fig. 2 is a similar view of a portion

of the engine showing a modification of the structure; Fig. 3 is a crankcase indicator diagram of an ordinary three-port engine; and Figs. 4 and 5 are crankcase indicator diagrams of engines constructed in accordance with the invention.

Referring to Fig. 1, the engine may be of well-known three-port two-stroke type, comprising cylinder casting 6 closed at the top by cylinder head 7 and at the bottom by oil pan 8. Piston 10 is operable in the usual manner, being connected by connecting rod 11 to crankshaft 12.

Piston 10 is shown in top center position. Piston 10 may be said to divide the space between cylinder head 7 and oil pan 8 into two chambers, 15 the cylinder or working chamber 9 above the piston, and the crankcase or pumping chamber 19 below the piston.

Piston 10 overruns inlet ports 18, bypass ports 21, and exhaust ports 22, in the usual manner, 20 well-known in three-port engines. Inlet ports 18 load from intake pipe 17 of considerable length. Bypass ports 21 lead from bypass 20 connecting pumping chamber 19 with working chamber 9. Exhaust ports 22 lead out of working chamber 25 9 to exhaust pipe 24.

If more freedom is desired in controlling the timing of inlet ports into pumping chamber 19, inlet pipe 17a, Fig. 2, may open directly thru ports 18a into pumping chamber 19, controlled by port 30 16 in a rotating web member on crankshaft 12a.

Operation of the engine on the two-stroke cycle, either Otto or Diesel cycle, is well understood. As a Diesel, piston 10, on the upward stroke compresses a charge of air in working 35 chamber 9 sufficiently to ignite the fuel when injected, and the resulting combustion drives piston 10 downward until ports 22 are opened, permitting the products of combustion to exhaust. This invention is concerned more with the pumping action in chamber 19.

In Figs. 3, 4, and 5, S is the stroke of piston 10, and the dot-dash line A indicates atmospheric pressure. Heights of ports 18 and 21 are denoted H—18 and H—21 respectively.

45 For comparison with the improvements of the invention, Fig. 3 shows the pumping action in the crankcase of an ordinary three-port two-stroke engine (without pipe 17 and with the ordinary short bypass connecting chambers 19 and 9 thru ports 21, the bypass only just long enough to get around piston 10, as usual). Piston 10, on its upward stroke toward top center in which it is shown, creates a depression in crankcase chamber 19 until ports 18 open, when 50 the depression is partially satisfied, but the pres-

sure in chamber 19 is still below atmospheric when ports 18 are closed by piston 10, by the amount 31. Crankcase compression starts from below atmospheric pressure, building up until ports 21 open, when part of this air is discharged around the piston thru a short bypass into working chamber 9. When ports 21 are closed by piston 10, the pressure in pumping chamber 19 is still above atmospheric by the amount 32, so that piston 10 has to go further upward to reduce the pressure below atmospheric, to induce another charge of air to enter when ports 18 open again. The pumping is inefficient at both ends of the stroke. The suction stroke starts from a pressure above atmospheric, and the pressure stroke starts from a pressure below atmospheric.

Conditions at one end of the stroke can be improved by the addition of a long enough inlet pipe 17. Fig. 4 shows pumping action in an engine with inlet pipe 17 and the ordinary short bypass connecting chambers 19 and 9 thru ports 21. Piston 10, on its upward stroke toward top center, creates a depression in crankcase chamber 19, as before, until ports 18 open, when air rushes in thru pipe 17, and the inertia of the column of air in pipe 17 forces more air into the crankcase, producing the overpressure 41 when ports 18 close. Crankcase compression starts from above the atmospheric line A building up to higher pressure during the downward stroke of piston 10, so that when ports 21 open, more air flows into cylinder 9. And yet, because the bypass is short, there is still an overpressure 42 in pumping chamber 19 when ports 21 close. Piston 10 has to go part way upward before pressure in chamber 19 is reduced to atmospheric. The suction stroke starts inefficiently as before. Conditions have been improved at one end of the pumping stroke but not at the other.

In the embodiment of the invention illustrated, intake pipe 17 serves to charge air thru ports 18 more efficiently, and long bypass pipe 20 serves to transfer the charge from pumping chamber 19 to cylinder 9 more efficiently. The pumping action is illustrated in Fig. 5. Piston 10 on its upward stroke toward top center, creates a depression in crankcase 19, until ports 18 open, when air rushes in thru pipe 17 and ports 18, building up velocity in the column of air in pipe 17, so that the inertia of the column forces more air into chamber 19, producing overpressure 51 when ports 18 close. Crankcase compression starts from above atmospheric pressure, building up a higher pressure, so that when ports 21 open, more air flows into cylinder 9 thru long bypass 20, which in turn builds up velocity. The inertia of the column of air in long bypass 20 sucks more air out of crankcase 19, producing underpressure 52 therein by the time ports 21 close. Thus when piston 10 starts upward on its suction stroke, there is already less than atmospheric pressure in crankcase chamber 19. Consequently the depression is greater than before, when ports 18 open. The pumping efficiency is improved at both ends of the stroke of piston 10, and its becomes possible to induce more air to flow thru the engine than its piston displacement, by the pumping action of the piston itself in crankcase 19.

It is true that piston 10, in producing greater air flow thru the engine by the aid of pipes 17 and 20 than would be possible without them, must do a little more work, but this slightly greater pumping loss is more than made up by the improvement in scavenging. It has been found possible by this invention to produce spe-

cific performance almost twice that usually possible with ordinary crankcase scavenging.

While specific embodiments of the invention have been shown and described it is understood that changes may be made in the arrangement and in the construction of the various parts, without departing from the spirit or scope of the invention as expressed in the following claims.

I claim:

10. 1. In a two-stroke engine having a cylinder and a crankcase with a piston operable therebetween, a port opening into said crankcase, means delaying the opening of said port until said piston has nearly completed its upward stroke, and a conduit opening into said port from air at a given pressure and so proportioned as to produce more than said given pressure in said crankcase when said port closes.
15. 2. In a two-stroke engine having a cylinder and a crankcase with a piston operable therebetween, a port opening into said crankcase, means delaying the opening of said port until said piston has nearly completed its upward stroke, and a tubular passage opening into said port from air at a given pressure such as atmospheric, said passage being long enough relative to the timing of said port to deliver more air to said crankcase and to produce more than said given pressure therein at the closing of said port.
20. 3. In a two-stroke engine having a cylinder and a crankcase with a piston operable therebetween, a port opening into said crankcase, means delaying the opening of said port until said piston has nearly completed its upward stroke, a conduit opening into said port from air at a given pressure and so proportioned as to produce more than said given pressure in said crankcase when said port closes, a port opening into said cylinder from said crankcase when said piston has nearly completed its downward stroke, and means associated with said last-named port and producing less than atmospheric pressure in said crankcase when said last-named port closes.
25. 4. In a two-stroke engine having a cylinder and a crankcase with a piston operable therebetween, a port opening into said crankcase, means delaying the opening of said port until said piston has nearly completed its upward stroke, a pipe of such length leading to said port as to produce more than atmospheric pressure in said crankcase when said port closes, a port opening into said cylinder when said piston has nearly completed its downward stroke, and a pipe of such length connecting said last-named port with said crankcase as to transfer more air from said crankcase to said cylinder and to reduce the pressure in said crankcase to less than atmospheric when said last-named port closes.
30. 5. A three-port two-stroke engine having a cylinder and a crankcase with a piston operable therebetween, one port opening into said crankcase and uncovered by the lower edge of said piston when nearing top center, a pipe opening into said port, from air at a given pressure and so proportioned as to produce more than said given pressure in said crankcase when said port closes, a second port in said cylinder uncovered by the upper edge of said piston when nearing bottom center, a bypass connecting said second port with said crankcase, and a third port in said cylinder opening outwardly to exhaust said cylinder as said piston approaches bottom center.
35. 6. A three-port two-stroke engine having a cylinder and a crankcase with a piston operable

therebetween, one port opening into said crankcase and uncovered by the lower edge of said piston when nearing top center, a pipe of considerable length opening into said port, a second port in said cylinder uncovered by the upper edge of said piston when nearing bottom center, a pipe of considerable length opening into said second port from said crankcase, and a third port in said cylinder opening outwardly to exhaust said cylinder as said piston approaches bottom center.

7. A three-port two-stroke engine having a cylinder and a crankcase with a piston operable therebetween and three ports controlled by said piston, one opening into said crankcase, the

second opening into said cylinder from said crankcase, and the third opening outwardly from said cylinder: the combination of a pipe leading to said first port of such length as to produce more than atmospheric pressure in said crankcase when said first port closes, a pipe leading to said second port from said crankcase of such length as to produce less than atmospheric pressure in said crankcase when said second port closes, and a pipe leading from said third port of such length as to assist in evacuating the exhaust from said cylinder.
